UNITED STATES PATENT OFFICE.

GEORGE WHIGELT, OF NEW YORK, N. Y.

DESIGN FOR A PAINT-MIXER FRAME.

45,215.

Specification for Design.

Patented Feb. 3, 1914.

Application filed August 20, 1913. Serial No. 785,790. Term of patent 14 years.

To all whom it may concern:

Be it known that I, GEORGE WHIGELT, a citizen of the United States, residing at New York, in the county of New York and State of New York, have invented a new, original, and ornamental Design for a Paint-Mixer Frame, of which the following is a specification, reference being had to the accompanying drawing, forming part thereof.

The figure is a perspective view of a paint mixer frame.

I claim:

The ornamental design for a paint mixer frame, as shown.

GEORGE WHIGELT.

Witnesses:

GEORGE VAN GILDER,
BERNARD BAUM.
